UNITED STATES PATENT OFFICE.

FRANK PAOLO MAZZEI, OF PETERSBURG, VIRGINIA.

STERILIZER FOR BARBERS' APPLIANCES.

1,228,464.

Specification of Letters Patent.

Patented June 5, 1917.

Application filed October 3, 1914. Serial No. 864,772.

To all whom it may concern:

Be it known that I, FRANK P. MAZZEI, a citizen of the United States, residing at Petersburg, in the county of Dinwiddie and 5 State of Virginia, have invented a new and useful Sterilizer for Barbers' Appliances; and I do hereby declare the following to be a full, clear, and exact description of the invention, such as will enable others skilled in 10 the art to which it appertains to make and use the same.

This invention relates to a new and useful apparatus for sterilizing various appliances, such as towels and the like and disinfecting 15 barbers' instruments, thereby insuring sanitation.

One of the features of the invention is the provision of sliding receptacles having 20 holders therein for the reception of the various barbers' instruments.

Another feature of the invention is the provision of disinfectant chambers in communication with each other, one of which is provided with means of communication with 25 said instrument holding receptacles, whereby the fumes of the disinfectant are applied to said instruments. The other disinfectant chamber is provided with means of communication to a shaving towel compartment for 30 applying disinfectant to the shaving towels.

Another feature of the invention is the provision of means for carrying the fumes from the disinfectant chamber to the mani- 35 curing instruments, which are received by a suitable receptacle.

Another feature of the invention is the provision of suitable receptacles for the reception of shampoo, steam and hair cloths or towels.

In practical fields the details of construction may necessitate alterations, falling 40 within the scope of what is claimed.

The invention comprises further features and combination of parts, as hereinafter set 45 forth, shown in the drawings and claimed.

In the drawings:—

Figure 1 is a view in perspective of the improved sterilizing apparatus constructed in accordance with the invention.

Fig. 2 is a vertical sectional view on line 50 2—2 of Fig. 1.

Fig. 3 is a sectional view on line 3—3 of Fig. 1 looking in the direction of the arrow a.

Fig. 4 is a sectional view on line 4—4 of

Fig. 1 looking in the direction of the arrow b.

Fig. 5 is a horizontal view on line 5—5 of Fig. 1.

Figs. 6 and 7 are enlarged detail views of 60 the instrument holding receptacles.

Referring more especially to the drawings, 1 designates the casing having hot water receptacles 2, in the upper portion of which brackets 3 are provided, for the support of a 65 perforated sheet metal plate 4. This sheet metal plate 4 divides the hot water chamber or receptacle into an upper receptacle 5, for the reception of towels to be steamed, which are used for steaming the face prior to mas- 70 saging. The receptacle 5 is provided with a hinged closure 6. The hot water chamber has in communication therewith the usual water gage 7, which is located upon the exterior of the casing 1. Below the hot water 75 chamber or receptacle is a heating chamber 8, in which the usual burner 9 is arranged, which is provided with a suitable connection 10 including a valve cock 11 for connection to any suitable gas supply (not shown). 80 The hot water chamber is also provided with a suitable connection 12 including a valve cock 13 for connection to a suitable water supply (not shown). A suitable valve cock 14 is connected to the water chamber, where- 85 by the barber may obtain hot water for various purposes in conducting his work in behalf of the patrons.

The casing 1 is provided with partition walls 15 and 16, between which and the walls 90 of the hot water chamber air spaces 17 are provided, in which the air may become heated from the hot water chamber. Be- 95 tween the front and rear walls of the casing adjacent the front and rear walls of the hot water chamber are air spaces 18 and 19, the air in which becomes heated from the heat of the hot water chamber. The walls 15 and 16 also divide the casing, so as to provide the compartments 20 and 21. In the com- 100 partment 21 guides 22 and 23 are provided for guiding and supporting the receptacles 24 and 25, which are perforated as shown at 26, and in which various holders are ar- ranged for holding the barber's tools or in- 105 struments. These receptacles 24 and 25 are received through the opening 27 of the cas- ing. Adjacent the lower portions of both of the compartments 20 and 21 are addi- 110 tional compartments 29 and 30 having

guides 31 for guiding and supporting the drawers or receptacles 32 and 33 which are designed to contain disinfectant material, such as formaldehyde. The upper wall of each of the compartments 29 and 30 is provided with perforations 34, through which the fumes from the disinfectant material pass into the dry air chamber 35. Leading from the dry air chamber 35 of the compartment 29 is a pipe or tubing 36, rising vertically adjacent one wall of the compartment 20, and projecting laterally from the tubing or pipe 36 are T-shaped tubes or pipes 38 and 39 extending laterally and over the receptacles or drawers 24 and 25, there being perforations 39 in the T-shaped pipes or tube, for projecting the fumes from the disinfectant material down upon the barber's instruments or tools in said receptacles or drawers 24 and 25. Extending from the dry air chamber 35 of the compartment 30 and extending laterally and rising vertically adjacent one wall of the compartment 21 is a pipe or tubing 40, the upper portion of which terminates in a T-shaped part 41 having perforations 42, for conveying the fumes from the disinfectant of the receptacle in the compartment 30 down upon the shaving towels in the compartment 21. The compartment 21 is provided with longitudinal bars 43, for the support of the shaving towels. A suitable closure or door 44 is hinged to the casing 1 for closing the compartment 21. The dry air chambers 35 are in communication by virtue of the pipe or tubing 45, which passes through the heating chamber, and extending downwardly from this pipe or tube 45 is a tube or pipe 46, the lower end of which is provided with a transverse portion 47 having perforations 48, for conveying the fumes from the disinfectant down upon the manicuring tools or instruments (not shown), which are designed to be carried in the drawer or receptacle 50, which is received upon and supported by the guides 51 in the lower portion of the casing 1. It will be observed that the compartments 20 and 21 are in communication, by virtue of the passage 53, which extends under the compartments 29 and 30 and under the heating chambers.

The compartments 29 and 30 are in communication by virtue of the pipe or tube 56, which passes through the heating chamber. Extending from the hot air spaces upon each side of the hot water chamber are pipes 57 and 58, which extend downwardly through the compartments 20 and 21 and open into the compartments 29 and 30, under the disinfectant containing drawers or receptacles 32 and 33, so as to keep the disinfectant well heated by hot dry air from the dry air spaces upon each side of the water chamber.

65 The upper portion of the casing 1 upon

each side of the steam towel receptacle is provided with a receptacle 60 having a hinged closure or cover 61. One of the receptacles 60 is designed to contain hair cloths or the like (not shown), while the other receptacle 60 is designed to contain shampoo towels (not shown). An angular pipe or tube 63 communicates between the compartment 20 and the steam towel compartment, so as to carry disinfectant fumes to the steam towels and the hair cloths, owing to the provision of the perforations 64. An additional angular perforated pipe or tube 65 communicates between the compartments 21 and the steam towel compartment, so as to also convey additional disinfectant fumes into the steam towel compartment and the shampoo towel compartment.

The disinfectant containing drawers or receptacles are provided with suitable fasteners or catches 66, so as to hold said receptacles in place.

Each of the receptacles 24 and 25 is provided with a clip 67 for grasping the handle of a brush and a portion of a comb, and also provided with a socket 68 for the reception of a portion of the head of the brush. In one end of each drawer 24 and 25 a pair of intersecting members 69 is fastened at 70. The end portions of the members 69 terminate in clamps 71, which engage the outer circumference of a shaving mug, for holding the same in place. Rising upwardly from the bottom of each drawer 24 and 25 opposite the end which holds the cup is a three legged bracket 72 provided with U-shaped extension clamps 73, which hold suitable razors, the lower ends of which are received by the arched clamps or sockets 74. Between the extension clamps 73 the handle ends of the scissors are clamped, while the ends of the blades of the scissors are received in the U-shaped clip 75. Also arranged in each drawer or receptacle 24 and 25 is a bracket 77 having a clip 78 for a hair dusting brush, and provided with a U-shaped clip 79 for the shaving brush. The bracket 77 is also constructed with the clamps 80 for receiving between them the clipping jaws of a pair of clippers, a portion of the handle of which is clasped in the clip 81. One end wall of each drawer 24 and 25 is provided with a loop 82 and the U-shaped clasp or clamp 83 for holding a caustic stick. Upon one side of each drawer or receptacle 24 and 25 is a loop 85 for holding a pair of tweezers.

The invention having been set forth, what is claimed as new and useful is:

1. In an apparatus for sterilizing barbers' articles, a casing having a central heat chamber, a compartment on each side of said chamber, means to support barbers' articles in the compartments, mixing chambers in the compartments below said sup-

porting means, disinfectant containers in the mixing chambers, tubes leading from the upper part of the heat chamber and communicating with said mixing chambers whereby the heat may surround the containers and cause the liberation of disinfecting fumes from the disinfectant, and means for conveying the disinfectant fumes to the articles and spraying said fumes on said articles.

2. In an apparatus for sterilizing barbers' articles, a casing, a central heat chamber therein, a compartment on each side of said chamber, means in the upper part of said compartments to support barbers' articles, disinfectant vaporizing chambers,

tubes rising upwardly from the mixing chambers and having means to spray the heated disinfectant fumes toward and upon the articles, and tubular means cross connecting the mixing chambers and having a tube extending downwardly through the heat chamber and terminating in a spray nozzle therebelow.

In testimony whereof I have signed my name to this specification in the presence of two subscribing witnesses.

FRANK PAOLO MAZZEI.
